UNITED STATES PATENT OFFICE

HEYMAN ROSENBERG, OF NEW YORK, N. Y.

APPARATUS FOR TREATING ARTICLES OF WORK

Application filed September 17, 1931. Serial No. 563,426.

This invention relates to improvements in the art of work handling and treating processes and apparatus of the type set forth in my co-pending application Serial No. 558,541, filed April 20, 1931, since patented June 6th, 1933, Patent No. 1,913,090, and has as its essential object the efficacious and expeditious as well as inexpensive handling and treating of work particularly in conjunction with heat treatment processes.

A further object is the grouping of work in a manner to assure treatment of a maximum quantity of work in a minimum area.

To this end, it is a further and more detailed object to handle the work as a continuous process, introducing work at one point, transferring work at another point, and removing the completed work at still another point.

With these and further objects in view as will in part hereinafter become apparent and in part be stated, the invention includes the step by step movement of work while being treated and the replacing and removal of work between steps.

The invention also includes apparatus for moving work along a path while being treated and removing the work from such path to a place of further treatment.

The invention still further contemplates the provision of means for mechanically transferring the work in moving it from one place of treatment to another.

The invention still further comprises certain other novel constructions, combinations, and arrangements of parts as will herein-after be more fully set forth and be subsequently specifically pointed out in the appended claims.

In the accompanying drawings,—

Figure 1 is a somewhat diagrammatic, sectional elevation of an apparatus embodying the features of the present invention and well adapted for the carrying out of the art.

Figure 2 is a horizontal section therethrough taken on the plane indicated by line 2—2 of Figure 1, and looking downward, parts being seen in plan and somewhat diagrammatically.

Figures 3, 4, 5, 6, 7, 8, and 9 are enlarged,

detailed, side elevations of a pair of transfer hooks with cooperating parts illustrating the successive steps in picking up, transferring, and depositing the work holders.

Referring to the drawings by numerals, 1 indicates any appropriate furnace and 2 a quenching vat, the furnace and vat being preferably provided with upstanding housings or enclosing hoods, not shown in the drawings, but extending sufficiently above the furnace and vat to accommodate the operations therein, after the manner of the housing disclosed in my co-pending application Serial No. 448,349, filed April 29, 1930. It should, of course, be understood that such hoods or housings are for the protection of the workmen, to vent poisonous gases, and other escaping fumes and heat. Doorways are, of course, provided in such housings to enable requisite access, and particularly provided to accommodate the movements of the loading and discharging arms hereinafter described, and such doorways are preferably closed by doors opened and otherwise moved relative to the movement of those arms by linkage connections or like actuators synchronized with the movements of the arms, after the manner seen in the actuation of the housing door operated by linkage from the discharge basket of my last above-mentioned co-pending application. Also, it will be understood that the quenching fluid in vat 2 may be water or oil, or any other appropriate quenching fluid, and will be preferably maintained at a relatively low temperature by means of appropriate cooling circulation, after the manner set forth in my co-pending application Serial No. 461,763, filed June 17, 1930.

An upright or standard 3 is mounted to resist lateral or tilting dislocation and upstands alongside the furnace 1, preferably opposite, that is across the furnace from, the vat 2. An arm 4 outstands laterally from the upper portion of standard 3 to overhang the furnace 1, and is provided with a terminal sleeve 5 at its free end, preferably substantially located in the line of the vertical axis of the furnace 1. A vertical shaft 6 extends through sleeve 5 and is provided with a fixed collar 7 having an end or thrust bearing on

- the upper end of sleeve 5 so as to support the shaft 6 with the lower end portion of the shaft extending down near the upper surface of the furnace 1 centrally thereof. Shaft 6 5 may be driven by any appropriate power or apparatus, one mode of actuating the same consisting of shafts 8, 9, and 10, having driving connections, such as beveled gears, and extending respectively across to and down 10 through the standard 3 and laterally out from the same, the shaft 10 being driven from any appropriate source of power, such, for example, as an alternating current motor or other means designed to insure synchronism 15 of motion of the parts to be actuated by shaft 6 with the motion of other parts hereinafter described.
- Fixed to and outstanding radially from the lower end portion of shaft 6 immediately 20 above the furnace 1 are work holder supports 13, 13, which may be in the form of forks as one convenient type of construction, but which essentially include spaced supporting walls or plates each notched at 14 with an 25 outward bevel for camming a work holder as hereinafter described.
- Work holders 15, 15 are provided, each consisting of any appropriate form of bracket apparatus having the work holder cross rod 30 16 at its upper portion engaging the beveled-face notches 14 of the two sides of a support 13. Each work holder 15 is adapted to detachably sustain pendent rods 15', 15' on which the work 17 is appropriately detachably mounted. The rods 15' may be mere bolts with nuts or heads at their lower ends and eyes or hooks at their upper ends, which eyes or hooks overhang and thus engage and are supported by the work holders 15. The 35 work 17 may be perforated discs, gear wheels, washers, or other annular or other shaped perforated bodies, or the work may be otherwise shaped and otherwise connected, preferably detachably, to the work holders 15.
- 40 A standard 18 similar in construction and arrangement to standard 3 upstands alongside or from the vat 2 preferably at the opposite side of the vat from the location of the furnace 1, and shafting 19, 20, and 21 delivers power to a pendent shaft 22, which is 45 similar in all respects to the shaft 6, and is synchronized in its movement therewith either by the employment of an alternating current motor for driving shaft 19, which is synchronized with the alternating current motor driving shaft 10, or the said shafts 19 and 10 may be hooked up to a common source of power geared to insure proper synchronization in the motion of shaft 6 with respect to the motion of shaft 22. Each of shafts 10 and 19 is, of course, driven by a step-by-step advance device proportioned to the requisite stepping of the respective work supports, an appropriate form and detailed construction of step-by-step device for

each of said shafts 10 and 19 being such as that seen in Figure 3 of my co-pending application Serial No. 580,158, filed December 10, 1931.

70 Fixed to and outstanding radially from the lower portion of shaft 22 are the supports 23 having the camming and work-holder-receiving recesses 24, the parts 23 being either in the form of forks or otherwise similar to the parts 13 to correspondingly cooperate with the work holders.

75 The supports 13 are located in that relation to the furnace 1 to enable the work 17 to be suspended substantially within the enclosure of the furnace from above, the upper or cover plate of the furnace being formed with an enlarged opening into which extends the pot 25.

80 Pot 25 may be supported in place in any appropriate manner, but preferably by the usual peripheral flange 26 overhanging a portion of the top of the furnace 1 and effectively sealing the top against the escape of fumes or heat. It should be understood that the present invention contemplates any

85 of a variety of treatments of work, more particularly heat treatments, and one of such treatments will serve to effectively illustrate the advantages of the present invention. For purpose of illustration, therefore, it is

90 stated that cyanide case-hardening may be very effectively carried out rapidly and economically, and in a most compact space by the present improved apparatus, and when cyanide case-hardening is being practiced, the pot 25 will be supplied with the required salt which will be, during operation, maintained molten and at the required temperature for effective carbon penetration of the work being treated.

95 100 105 The supports 23 lie immediately above the vat 2 in position for allowing the work 17 to be suspended in the quenching fluid for providing the desired reaction after the cyanide treatment, assuming a case-hardening process to be illustratively in progress.

110 The furnace 1 and vat 2 may be connected together by any appropriate framework and provided with any desired partitions or cover plates, such as plates 27 and 28, and a rock shaft 29 is preferably journaled to oscillate in appropriate bearings 30, 30, carried by the plate 28 or by the plates 27 and 28, according to preference. Fixed to the rock

115 shaft 30 is an operating lever arm 31, which is constructed to function similarly to the work transfer lever arms 19 and 21 of my above-mentioned co-pending application Serial No. 558,413. The arms of the said co-pending application are shown in pairs, so

120 125 130 that the work swings between them; whereas in the instant disclosure a single arm is employed and the work is adapted to swing alongside, but, of course, it is well within the intent and purpose of the present invention that a pair of arms may be employed after

the manner taught in the said co-pending application when and if preferred. Extending laterally from the free end of arm 31, and preferably rigidly carried thereby, is 5 a pin 32 on which is pivotally mounted preferably a pair (seen in top plan in Fig 2) of hooks 33, each having a counterbalance weight 34 and constructed and adapted to operate as set forth in detail in my last above-mentioned co-pending application. The pair of hooks 33 are connected to function as a unit and may be considered a single hook except that they accommodate between them the pendent bar of the bracket making up 10 the work holder 15 and which extends downward from the work holder cross rod 16.

The axis of rotation of rock shaft 29 and the length of arm 31 to the axis of rotation of the hooks 33, which are swivelled to swing 20 freely on pin 32, is such as to cause the hooks to have the requisite relationship to the cross bars 16 to produce effective operation of the hooks in picking up the bars from supports 13 and discharging the bars on to supports 23 as the arm 31 is swung from the position overhanging pot 25 to the position overhanging vat 2. To effect such swinging movement of arm 31, the shaft 29 is driven by 30 an electric motor or other appropriate source of power 35, controlled by an automatic reversing switch 36, or other leverage apparatus for causing the shaft 29 to oscillate through the required angle for moving the arms 31 back and forth between its extreme 35 positions over the pot 25 and over the vat 2. The shaft 29 extends beyond the bearing 30 at one side and into a housing 37 provided with appropriate gearing, not illustrated, but such as is shown in my co-pending application filed September 11, 1931, 40 Serial No. 562,394, which connects with a stub shaft 38 carrying a hand-operating lever 39 for enabling emergency, manual actuation of the shaft 29.

The hooks 33 are caused to pick up and let go of the work after the manner set forth and claimed in my co-pending application Serial No. 558,413, but may be briefly stated as illustrated in detail in Figures 3 to 9 of the drawings as follows: Lever 31 moves downward toward the cross bar 16, as seen in Figure 3, while the cross bar is supported by parts 13 over pot 25 until the camming surface 43 at the front of the bite of the hooks strikes the bar, as seen in Figure 4, and causes the hook to ride backward, that is in the direction toward shaft 29, past the bar. Since the hooks are suspended to hang normally as seen in Figure 3, the movement during this camming action is away from the normal, gravity-sustained position of the hooks, and as soon as the shank of the hook passes bar 16 in moving downward, the hook will drop into line below the bar 16, and the first slight upward movement of lever 31

will then bring the hooks to the position seen in Figure 5. Further upward movement will cause the hooks to move to the position seen in Figure 6, while the work swings alongside lever arm 31 and finally assumes a 50 pendent position above the work supports 23. The further vertical movement of arm 31 causes the work to be lowered between the pair of supports or fork 23 until the bar 16 strikes the camming surface 24 of the respective supports 23, as seen in Figure 7. The weight of the work holder 15 and of the work 55 17 causes the bar 16 to slide down the camming surface and thus swing the hooks 33 out of balance to the position seen in Figure 8. The arm 31 then moves a little lower down, and the hooks 33 swing by gravity to a position laterally of bar 16, as seen in Figure 9. The arm 31 is then free to swing back to its load-receiving position.

Thus, with the swinging of the arm 31 back and forth between its extreme positions respectively above pot 25 and above vat 2, successive work holders will be lifted from the pot and delivered to the quenching vat, 60 and it should be understood that during operation the shafts 6 and 22 will be revolved with a step by step motion to advance a fork or pair of supports 13 one step after a work holder has left and freed itself from the line 65 of travel of the supports 13, so that, when the hooks 33 return, a new work holder will be in line to be engaged, and likewise the shaft 22 will be advanced with a step by step movement timed and synchronized to 70 present an empty pair of work supports or fork 23 with the approaching of the new work holder and work suspended from hooks 33.

Of course, as the work is being continuously removed from the supports 13 and continuously supplied to the supports 23, the quenched work 17 in vat 2 must be removed successively from the forks or supports 23 and new work must be successively supplied 75 to forks or supports 13, and this may be done manually, if desired, but it is preferable to deliver work to the supports 13 mechanically and to remove work from supports 23 mechanically both as time, cost, and material saving, and as a means of avoidance of exposure of operators to possible injuries from fumes in the plant.

To the end of providing for mechanical work feeding and work removal, shafts 41 and 42 are journaled in appropriate bracket bearings, or other appropriate supports, carried by the plates 27 and 28, or other framing of the plant, and the shafts 41 and 42 are driven from any appropriate source of power 80 synchronized to cooperate with the action of shaft 29. To this end, the shaft 29 may, as seen in Figure 2, be extended beyond its geared connection with its motor 35 and geared to the shafts 41 and 42 in a manner to 85

actuate the latter shafts in opposite directions at the same time. In other words when shaft 41 is rocking clockwise, shaft 42 will be rocking counter-clockwise. Shaft 42 is provided with a feeding arm 40 carrying a pair of hooks 44 identical in construction and mounting with hooks 33, except that the spacing of the axis of rotation of shaft 42 relative to the pivotal axis of hooks 44 is such 10 with respect to the recesses 14 of supports 13 as to be the same as the relation of the hooks 33 with respect to the recesses 24 of supports 23. In other words, the spacing is such that the hooks 44 perform their let-go 15 operation relative to the supports 13, just as the hooks 33 perform their let-go operation relative to the supports 23, as seen in Figures 7, 8, and 9. Likewise, the shaft 41 carries a discharge arm 45 supporting a pair of pick-up and let-go hooks 46 similar in construction and operation with the hooks 33, except that the spacing is such that the hooks 46 pick up the rods 16 and work holders 20 from the supports 23 just as hooks 33 25 pick up the rods from the work holders 13, and, of course, the let-go of the hooks 46 is accomplished outside of the plant or the work may be manually removed, if preferred. Likewise work may be manually 30 supplied or mechanically supplied to the hooks 44 in their take-up action at the outer extremity of their stroke when they are preparing to bring in a new work holder to the new set of supports 13.

35 Thus, the arms 31, 40, and 45 and their respective work-carrying hooks and the shafts 6 and 22 are all effectively synchronized to cooperate, and are so coordinated that a work holder is delivered to a pair of supports 13 40 during the cessation of rotation of shaft 6 between each two steps thereof, and a work holder is similarly removed from a pair of the work supports 23 during each cessation between the steps of the shaft 22, and during 45 the same period the hooks 33 transport a work holder from the supports 13 to the supports 23. Naturally, the work-feeding and discharging arms may be located at any preferred point, but it is desirable to allow the 50 work to be exposed to the cyanide action for a substantial time where a cyanide process is being carried out, and while it is not necessary usually to retain the work any appreciable time in the quenching vat 2, the presence 55 of the work therein will do no harm, and as a matter of convenience of assemblage, the work-feeding and work-removing arms 40 and 45 are, therefore, preferably located at the same side of the plant, but may be otherwise located as desired.

60 By actual comparative tests, the present invention is capable of handling an enormous quantity of work in an extremely compact space. For example, when cyanide treating 65 metal work for case-hardening purposes, I

can treat more work in a plant incorporating the present invention in any given time than can be treated with the continuous conveyor type tank of far greater size. By way of illustration, a plant embodying the present 70 invention and having a cyanide pot, such as pot 25, which is only fifty inches in diameter and eighteen inches deep will handle a very substantially greater amount of work in any given time than can be handled in a continuous conveyor tank type which is fourteen feet long. Of course, it will be understood that 75 factory space is of value and frequently of great value.

It will be understood from the foregoing, 80 of course, that the standard 18 is provided with the lateral arm 47 and sleeve 48 corresponding to arm 4 and sleeve 5, and that the shaft 22 is journaled in the sleeve 48 and supported thereon by the thrust-bearing stop collar 49 similarly to the supporting of shaft 6 by collar 7.

What is claimed is:—

1. In apparatus for treating articles of work, the combination of a pot, work supporting and moving means for moving work in a continuously advancing direction with a step-by-step movement in a circular path within the pot, and means for removing work 90 from the pot while leaving the work supporting and moving means in position to support newly supplied work in the pot.

2. In apparatus for treating articles of work, the combination of a pot, work supporting and moving means for moving work in a continuously advancing direction with a step-by-step movement in the pot, a cooperating vat, work supporting and moving means for moving work in a continuously advancing direction with a step-by-step movement in the vat timed to coordinate with the step-by-step movement of the work in the pot, and means for transferring work from the work supporting and moving means of the 100 pot to the work supporting and moving means of the vat in the interim between steps and while leaving both of said work supporting and moving means in operative work supporting position.

3. In apparatus for treating articles of work, the combination, with a pot, of sustaining means disposed above the pot, work supporting and moving means movably supported by said sustaining means and outstanding to overlie the pot, the said work supporting and moving means having camming surfaces, and pick-up and let-go means for moving work carriers to and from engagement with said work supporting and moving means in position for enabling the camming means to gravity locate the work carriers relative to such pick-up and let go means.

4. In apparatus for treating articles of 130

work, the combination, with spaced treatment means, of work supporting and moving means for each treatment means for moving work in a continuously advancing direction, 5 and pick-up and let-go work-transfer means for delivering work successively to the work supporting and moving means of one of the treatment means, for delivering work similarly successively from said last-named work 10 supporting and moving means for one of the treatment means to the work supporting and

moving means of another of said treatment means, and for transferring work similarly successively from the last-mentioned work supporting and moving means, all while leaving all of said work supporting and 70 moving means in the proper relation to the treatment means for supporting work being or to be treated.

In testimony whereof I affix my signature. 75

HEYMAN ROSENBERG.
